UNITED STATES PATENT OFFICE

HARRY W. BUNDY, OF DETROIT, MICHIGAN, ASSIGNOR, BY MESNE ASSIGNMENTS, TO
BUNDY TUBING COMPANY, OF DETROIT, MICHIGAN, A CORPORATION OF MICHIGAN

METHOD OF FORMING FINNED TUBE INTO SHAPES

Application filed February 6, 1928. Serial No. 252,222.

This invention relates to a method of forming finned tube into shapes.

Finned tubing is advantageous for the purpose of heat exchange. Such tube can be used in heating radiators, radiators for the cooling system for internal combustion engines, and one of the later uses for such tube is for condensing units for mechanical refrigerators.

10 A finned tube, however, and especially a finned tube where a helical fin is sealed to the tube, or adjacent convolutions thereof sealed together, as by means of sealing metal such as solder, does not possess good bending qualities, but offers material resistance to being bent or formed into suitable shapes for the purpose of being used in heat exchanging units.

Accordingly, the present invention contemplates a method by means of which finned tubing can be easily and nicely formed into any desired shape and then set in this shape. The invention contemplates the making up of a finned tube by leaving the parts thereon unsealed or not bound together, and while in this condition the tube is shaped as desired and then the parts are sealed. By sealing the tube at this time the tube per se is completed and also it is set into the shape into which 30 it was previously formed.

In the accompanying drawings:

Fig. 1 is a side elevation of a coiled finned tube showing one shape in which the finned tube may be formed for use in a condenser 35 unit for a mechanical refrigerator.

Fig. 2 is a view partly in side elevation and partly in section showing one form of finned tube which can be treated in accordance with this invention.

40 Fig. 3 is a diagrammatical view illustrating one manner in which previously shaped tube can be subjected to a bath of sealing metal.

Fig. 4 is a view illustrating another shape 45 into which the tube may be bent.

Fig. 5 is a view partly in side elevation and partly in section illustrating another kind of tube which can be used in following the method.

50 One form of finned tube which may be

utilized is shown in Fig. 2. This finned tube is made up of stock which is angular in cross section and helically wound. One leg of the angular stock forms a helical fin 1. The adjacent convolutions of the other leg 2 are overlapped thus forming a tubular body 3. One manner in which this tube is made is fully described in my copending application Serial No. 200,273, filed June 20, 1927.

A suitable length of this tube thus formed 60 may now be taken and formed into any desirable shape to fit the needs to which it is to be put. It may be shaped into the form of a spiral coil, as shown in Fig. 1; it may have a circular shape, as indicated in Fig. 3; 65 or it may have a U-shape as illustrated in Fig. 4. Any one of a multiplicity of shapes can be used. The tube is quite easily shaped due to the fact that the adjacent convolutions are not sealed together. After the length of 70 finned tube is shaped as desired, it is then subjected to a bath of sealing metal such as solder. This may be accomplished by dipping the tube into molten metal 4 contained in a tank 5. When the tube is bent into relatively simple shapes, as illustrated in Figs. 3 and 4, it can be held by hand during the dipping. Where, however, more complicated shapes are desired, which may involve 75 relatively sharp curves, suitable guide devices or braces of any desirable character can be used.

When the shaped tube is thus subjected to the bath of sealing metal, it will be noted that two things are accomplished. One is 85 the completion of the tube per se; in order to make a tube constructed as shown in Fig. 2 fluid tight, the overlapping convolutions must needs be sealed together. It is well understood by those versed in the art that molten sealing metal finds its way in between the overlapping parts. The other thing accomplished is, the shaped tube is given a set. In other words, after the tube has been subjected to its bath of sealing metal and then 90 removed, the finned tube retains its shape upon the cooling of the sealing metal.

Preferably, when the length of shaped tube is thus dipped, the tube is somewhat longer than necessary so as to provide portions 100

which extend out from the bath by means of which the shaped tube can be handled. These portions can be cut off and then part of the helical fin removed adjacent the end to permit of attaching of suitable fixtures thereto.

Another kind of tube which can be shaped in accordance with this invention, is shown in Fig. 5 wherein a preformed tubular body 6 is used and upon which is wound fin stock angular in section, one leg of the angle forming a helical fin 7 and the other forming a helical band 8 lying directly on the preformed tube. This tube can be nicely bent and shaped before the helical fin stock is sealed to the tubular body, and it has been found that such a tube can be bent into a curve sharper than can the tube 6 without the helical fin, because the helical fin stock reinforces the tube and prevents the same from collapsing or buckling in a sharp angle where the curve is effected. Moreover, as set forth in my co-pending application Serial No. 205,593, filed July 14, 1927, the inner tube 6 can be made of relatively light stock inasmuch as the fin stock affords a material reinforcement therefor. Such a tube is capable of being shaped as desired and then subjected to a bath of sealing metal in a manner as above described.

By way of example, two forms of finned tube construction have been shown, but it is within the invention to utilize finned tube differently constructed; thus, the overlapped or helical windings of Fig. 2 need not be sufficient to provide a double wall such as shown, but may be just sufficient to provide overlapping surfaces for securing purposes. Moreover, the helical stock on the tube shown in Fig. 5 need not be wound so close together, but the several convolutions thereof may be spaced apart.

Claims:

1. The method of forming finned tube into shapes and finishing the tube which comprises, forming the finned tube and leaving the parts unsealed, forming the tube substantially into the desired shape and then subjecting the same to a bath of sealing metal to finish the tube by sealing the parts together and to set the tube into the shape in which it was formed.
2. The method of forming finned tube into shapes, which comprises making a tube having a fin composed of helically wound stock, shaping the tube into the desired shape before the helical windings of the fin are sealed to the tube, and then setting the tube and sealing the fin winding by subjecting the shaped tube to a bath of sealing metal.
3. The method of forming finned tube into shapes, which comprises making a tube having a fin composed of helically wound stock, shaping the tube into the desired shape before the helical windings of the fin are sealed to the tube and while the tube can be easily thus

shaped, and then dipping the shaped tube into a bath of molten sealing metal to set it into said shape and seal windings to the tube.

4. The method of forming finned tube into shapes, which comprises making a tube having a fin composed of helically wound stock, shaping the tube into the desired shape before the helical windings of the fin are sealed to the tube and while the tube can be easily thus shaped, dipping the shaped tube into a bath of molten sealing metal and then allowing the sealing metal to harden to set the tube into the said shape and finish the tube by sealing adjacent parts together.

5. The method of forming finned tube into shapes, which comprises making a finned tube which includes a tubular body and a helical fin thereon, at least one of which is formed by helically wound strip stock, leaving parts of the finned tube unconnected, shaping a length of this finned tube into the desired shape, and then subjecting the same while in such shape to a bath of molten sealing metal to seal the fin to the tubular body and to set the length of finned tube into the shape in which it was formed.

6. In the art of forming heat exchange devices or the like out of finned tubing, the method comprising the taking of a tubular body with a helical fin thereon and bending the same substantially to the shape of the device to be formed before the fin is fixedly secured to the tubular body, whereby relative sliding movement between the tubular body and the helical fin may take place so that the finned tubular body may be readily formed into curves or the like without rupture, and then after the device has been thus formed, fixedly securing the helical fin and the tubular body together by molten sealing metal.

7. In the art of forming heat exchange devices or the like out of finned tubing, the method comprising the taking of a tubular body with a helical fin thereon and bending the same substantially to the shape of the device to be formed before the fin is fixedly secured to the tubular body, whereby relative movement between the tubular body and the helical fin may take place so that the finned tubular body may be readily formed into curves or the like without rupture, and then after the device has thus been formed, fixedly securing the helical fin and the tubular body together by dipping the formed device while it is retained in its form, in a bath of molten sealing metal.

8. In the art of forming heat exchange devices on the like out of finned tubing wherein the tubing consists of a tubular body and the fin is footed so that the foot portion lies next adjacent a tubular body and cooperates to form a strengthened tubular wall, the method comprising the taking of this finned tube and bending it substantially into the shape of the device to be formed before the tubular

body and the fin are fixedly secured together, whereby relative movement may take place so that the finned tubular construction may be readily formed in curves or the like without rupture and then after the tubular construction has been thus formed, fixing the fin and tubular body portion together and setting the tubular construction into the shape in which it has been formed by molten sealing metal.

9. In the art of forming heat exchange devices or the like out of finned tubing wherein a tube is utilized having wound around its exterior surface fin stock L-shaped in cross section with one leg of the L abutting against the tube, the method comprising the taking of this finned tube construction and bending the same substantially into the shape of the device to be formed before the tube body and fin are fixedly secured together, whereby relative sliding movement between the tube body and fin may take place so that the finned tube may be readily formed into curves or the like, without rupture, and then securing the tube and fin together and setting the same into its formed shape by the application thereto of a molten sealing metal.

In testimony whereof I affix my signature.
HARRY W. BUNDY.
